UNITED STATES PATENT OFFICE.

ALFRED F. KANE, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed April 10, 1923. Serial No. 631,132.

To all whom it may concern:

Be it known that I, ALFRED F. KANE, a citizen of the United States of America, residing at New York, in the county of Bronx and State of New York, have invented certain new and useful Improvements in Telephone Systems, of which the following is a full, clear, concise, and exact description.

10 This invention relates to telephone systems and more particularly to switching apparatus of the so-called coordinate type.

Heretofore in systems of this type as disclosed in a copending application of E. H. 15 Clark, Serial No. 608,139, filed December 21, 1922, it has been proposed to distribute traffic over a plurality of common connecting links by assigning a group of connecting link circuits to a group of subscribers' lines, 20 and providing a separate starting conductor for each line, and a relay for each group of links for connecting each of said starting conductors to a different one of said links, from whence the selection of an idle link by 25 said lines may proceed.

From the foregoing it is evident that the even distribution of wear on a group of connecting links depends upon the manner in which calls emanate from the lines having 30 access to the group of links, that is, in order to have an absolutely even distribution of wear on the connecting links it is necessary that subscribers on the lines associated therewith initiate calls in a certain sequence, a 35 condition which will be rarely met with in practice.

It is, therefore, an object of this invention to evenly distribute the wear on the connecting links of a coordinate switch, irrespective of the manner in which calls, which 40 are to be handled by the links, are initiated.

The foregoing object of this invention is obtained by providing each link in a group with a link relay, and a common locking circuit for all such relays in a group which is controlled by the last relay in the group, so that as each link has been seized for use its associated link relay locks up under control of the last link relay in the group, thereby 50 rendering the link associated therewith inaccessible to incoming calls until all other succeeding links have been utilized in extending connections. The operation of the controlling link relay opens the common locking circuit and permits all the individual 55

link relays to release, thereby again rendering the links successively accessible to incoming calls. By this arrangement no link connector can be employed a second time until all other link connectors in the group 60 have been used once in extending connections.

Other features and advantages as are contemplated by the present invention will be clearly understood from the following detailed description and by reference to the accompanying drawings in which Fig. 1 shows two groups of incoming lines, and Fig. 2 shows two groups of link circuits adapted to interconnect the lines incoming 70 from the groups shown in Fig. 1 with the outgoing trunks shown on the right of Fig. 2.

The following description is directed only to the operation of the circuits employed in switches of this type, but a clear understanding of the type of mechanical apparatus, which may be employed in connection with these circuits, may be had from the British patent No. 183,438, issued to Western 80 Electric Company, Limited, accepted September 6, 1923.

Referring to the drawing, there are shown two groups of two incoming lines, the upper group containing lines 20 and 21 and the 85 lower group containing lines 22 and 23.

Let it be assumed that the subscriber on line 21 wishes to establish a connection. The following description will show how upon the removal of the receiver on line 21 this 90 line will be automatically connected to trunk 100.

The calling subscriber on line 21 removes the receiver from the switchhook and establishes a circuit for the energization of line 95 relay 24. This circuit extends from grounded battery, left-hand winding of relay 24, back contact and outer armature of cut-off relay 25 over the closed loop of line 21, inner armature and back contact of relay 25 and 100 thence to ground through the right-hand winding of line relay 24. The operation of relay 24 establishes a circuit from grounded battery, winding of vertical line magnet 28, conductor 29, armature and front contact of line relay 24, winding of relay 26, normal make-before-break contacts of relay 26, conductor 27, conductor 30, back contact and upper armature of relay 31, conductor 32 to ground over the back contact and upper 110

armature of relay 33. Relay 26 energizes in this circuit and in attracting its armature establishes a circuit which may be traced from grounded battery, winding of vertical line magnet 28, conductor 29, armature and front contact of line relay 24, winding of relay 26, front contact and armature of relay 26, conductor 54, winding of relay 31, conductor 32 to ground over the back contact and upper armature of relay 33. Relay 31 operates in this circuit and at its upper armature interrupts the original energizing circuit for relay 26, and at its lower armature establishes an obvious circuit for relay 35.

The operation of magnet 28 in the circuit previously traced rotates its associated line bar and prepares for operation the insulating pieces such as 36 shown in the vertical line above magnet 28. Magnet 28 in attracting its armature closes a circuit from ground, front contact and inner left-hand armature of magnet 28, conductors 37 and 38, back contact and outer left-hand armature of slow-releasing relay 39, winding of trunk bar magnet 40 to battery and ground.

Magnet 40 operating in this circuit, causes the rotation of its associated trunk bar and prepares for operation the insulating pieces such as 41 common to the trunk bar, and respectively individual to the several links. Magnet 40 in operating establishes a locking circuit for itself which extends from grounded battery, winding of magnet 40, inner armature and back contact of relay 42, front contact and innermost armature of magnet 40, conductor 37 to ground over the inner left-hand armature and front contact of magnet 28. This locking circuit is necessary owing to the fact that upon the energization of magnet 40 a circuit is established from ground, middle armature and front contact of magnet 40 to battery and ground through the winding of slow-releasing relay 39 causing the operation of this relay and the opening of the original energizing circuit for magnet 40.

The operation of relay 35, as described, as a consequence of the operation of line relay 24 causes the attraction of its armature thereby establishing a circuit for link magnet 43 which may be traced from grounded battery, winding of magnet 43, conductor 55, back contact and right-hand armature of relay 54, front contact and armature of relay 35, conductor 47, front contact and outer left-hand armature of magnet 28, conductor 53, front contact and outermost left-hand armature of magnet 40, to ground. Magnet 43 becomes energized in this circuit and causes the movement of the cards 36 and 41, which as hereinbefore described, have been conditioned for operation by the actuation of the vertical line and trunk magnets 28 and 40, respectively. The actuation of the

cards 36 and 41 effects the establishment of a circuit from the line conductors 56, 57 and 58 leading from station 21 through the link conductors 59, 60 and 61 respectively to the trunk conductors 62, 63 and 64 respectively. A circuit is now established from ground, front contact and right-hand armature of slow-releasing relay 39 over conductor 64, link conductor 61, line conductor 58, to battery and ground through the winding of cut-off relay 25. A circuit may also be traced from ground on link conductor 61 over conductor 65, right-hand winding of relay 54, conductor 55 to battery and ground through the winding of magnet 43, which circuit forms a means for maintaining magnet 43 operated during the use of the talking circuit. Relay 54, however, does not become immediately energized in this circuit due to the fact that its right-hand winding is short-circuited by the extension of ground from the armature of trunk bar magnet 40 as hereinbefore described.

Upon the energization of cut-off relay 25, line relay 24 becomes deenergized resulting in the deenergization of relays 26, 31 and 35 and magnet 28, whereupon the short-circuit about the right-hand winding of relay 54 being removed, this relay becomes energized and at its right-hand armature transfers the control of conductor 47 from magnet 43 to magnet 44. In attracting its left-hand armature relay 54 establishes a locking circuit for itself which may be traced from grounded battery, left-hand winding, front contact, and left-hand armature of relay 54 to ground over the left-hand armature and back contact of relay 110, the purpose of which will hereinafter be explained.

As soon as the line 21 is extended to the trunk 100 a circuit through the winding of relay 42 is completed over the substation loop and this relay remains energized during the establishment of the connection. Relay 42 opens the locking circuit for magnet 40 which releases a switching bar associated therewith. Relay 42 also maintains relay 39 operated by placing a ground on the winding of relay 39 as a substitute for the original ground placed there by the middle armature of magnet 40. The connection between line 21 and trunk 100 is maintained by the continued energization of relay 39 which controls the link bar serving the link 101.

When the subscriber on line 21 replaces the receiver on the switchhook and opens the loop of this line, relay 42 becomes deenergized and shortly thereafter relay 39 retracts its armatures removing ground from conductor 64, allowing magnet 43 and cut-off relay 25 to become deenergized whereupon all the apparatus with the exception of relay 54 is restored to normal.

When trunk 100 is found busy relay 39 is energized so that a second call initiated in any subgroup of lines will seize trunk 105 through a circuit extending through the 5 innermost armature and back contact of magnet 40, inner left-hand armature and front contact of relay 39, back contact and outer left-hand armature of relay 75 to battery and ground through the winding of 10 magnet 76. Magnet 76 functions in a manner similar to magnet 40 as hereinbefore described.

It is to be noted that when relay 54 is energized, and locks up under the control 15 of relay 110 a call emanating from line 20, which would effect the operation of vertical line magnet 70, would be handled over conductor 47 as before, but the circuit for magnet 43 would be found open at the right- 20 hand back contact of relay 54 whereupon the connection would be transferred to link 102 by the energization of magnet 44 over the right-hand armature and front contact of relay 54 and right-hand armature and 25 back contact of relay 90. This condition prevails whether or not link 101 is still in use since relay 54 locks up independently of magnet 43 and remains energized after link 101 has been released and until links 30 102, 103 and 104 have been sequentially employed in extending connections.

As soon as the link 104 has been seized for the extension of a call and magnet 46 has locked up under the control of a relay 35 such as 39, relay 110 becomes energized in a manner similar to that described in connection with relay 54. Relay 110 in attracting its left-hand armature interrupts the common locking circuit for relays 112, 40 90 and 54 permitting these relays to release and rendering the links 101, 102 and 103 again successively accessible to incoming calls. From the foregoing it is evident that the system disclosed provides for 45 the absolute even distribution of wear on the link connectors in a group irrespective of the manner in which the calls emanate from the lines having access to the group.

Some of the general features of this system which are included in the British patent mentioned above are first, the lines in a vertical or longitudinal row above magnet 28 form one digital subgroup and, second, the lines in a horizontal or transverse row 55 to the right of the group of magnets 43 to 46 form another digital subgroup. These subgroups may be said to be in the two principal directions of a two coordinate system and hence in a hundred line main 60 group there will be twenty digital subgroups ten of which will be characterized by a tens digit, and the remaining ten will be characterized by a units digit.

All the link circuits have access to the 65 trunks such as 100 and 105. The link cir-

cuits are, however, divided into groups and each group of link circuits is individual to a particular group of lines in one direction of the two coordinate system, thus the group of link circuits including links 101, 102, 103 70 and 104 is individual to the particular group containing lines 20 and 21, etc., and forms a row of contact sets for each line and trunk bar.

It should be noted that magnet 28 upon 75 energizing opens its outer right-hand armature contacts and removes battery potential from the winding of all other magnets corresponding to magnet 28 such as magnets 70, 51, 93 and 52, etc., serving other lines 80 of the same or another subgroup as for example lines 20 and 22, so that should a call be simultaneously initiated upon another line served by such other magnets no interference will result and the possibility 85 of double connections to the same link circuit is obviated. In like manner the remaining magnets 70, 51, 93 etc., disconnect battery from all other magnets succeeding them in order in such a manner that it is not possible 90 for two such magnets to become energized at the same time, the magnet nearest the source of potential being given the preference.

If two lines in different groups, for example, lines 21 and 23 both served by the same magnet 28 call simultaneously the connection of both lines to the same trunk circuit through different link circuits is prevented since it is not possible for link bar magnets 100 such as 43 and 95 serving respectively the groups of lines in which lines 21 and 23 terminate to become simultaneously operated. The simultaneous operation of magnets 43 and 95 during the operation of trunk bar 105 magnet 40 (such operations would permit lines 21 and 23 to be simultaneously connected to trunk 100) is prevented by the operation of relay 33, which at its upper armature opens the initial energizing circuit for 110 relay 26 which controls the operation of relay 31. Thus if lines 21 and 23 simultaneously initiate calls line 23 will have preference, but if line 21 initiates a call just a small fraction of a second prior to line 23, 115 relay 31 will have become operated and will have opened the initial energizing circuit for relay 98.

What is claimed is:

1. In a telephone system, a plurality of incoming lines, a group of link circuits, a relay common to all of said lines, a relay individual to a particular one of said lines, and means effective upon the conjoint operation of said relays to select one of said link 120 circuits to cooperate with one of said lines in establishing a telephonic connection, and to render the selected link inaccessible for other connections until all the links in said group have been employed. 130

2. The combination in a switching system of line circuits, link circuits, trunk circuits, line bars serving said lines, link bars serving said links, a trunk bar for each of said trunks, means for causing the joint operation of a line bar, a link bar and a trunk bar, said bars cooperating with each other in connecting a line to a link and such link to a trunk, and means for rendering a selected link inaccessible until all of said links have been used. 40
5. The combination in a switching system of line circuits, link circuits, trunk circuits, contact sets, line bars serving said lines, link bars serving said links, a trunk bar for each of said trunks, means for causing the joint operation of the line bar, a link bar and a trunk bar, said bars cooperating with each other in actuating said contact sets to connect a line to a link and such link to a trunk, and means for rendering a selected link inaccessible until all of said links have been used. 45
10. The combination in a switching system of line circuits, link circuits, trunk circuits, line bars serving said lines, link bars serving said links, a trunk bar for each of said trunks, means for causing the joint operation of a line bar, a link bar and a trunk bar, said bars cooperating with each other in connecting a line to a link and such link to a trunk, and means for rendering a selected link inaccessible until all of said links have been used. 50
15. The combination in a switching system of lines divided into subgroups, a group of links for each subgroup of lines, trunks serving all of said links, line switching members each serving a line in each subgroup, link switching members individual to said links, trunk switching members individual to said trunks, means for causing the joint operation of one of each of said switching members to connect a line to a link and such link to a trunk, and relay means for rendering a selected link inaccessible until all of said links have been used. 55
20. The combination in a switching system of lines divided into subgroups, a group of links for each subgroup of lines, trunks serving all of said links, line switching members, each serving a line in each subgroup, link switching members individual to said links, trunk switching members individual to said trunks, means for causing the joint operation of one of each of said switching members, and relay means for rendering a selected link inaccessible until all of said links have been used. 60
25. The combination in a switching system of lines divided into subgroups, a group of links for each subgroup of lines, trunks serving all of said links, line switching members, each serving a line in each subgroup, link switching members individual to said links, trunk switching members individual to said trunks, means for causing the joint operation of one of each of said switching members, and relay means for rendering a selected link inaccessible until all of said links have been used. 65
30. The combination in a switching system of lines divided into subgroups, a group of links for each subgroup of lines, trunks serving all of said links, line switching members, each serving a line in each subgroup, link switching members individual to said links, trunk switching members individual to said trunks, means for causing the joint operation of one of each of said switching members, and relay means for rendering a selected link inaccessible until all of said links have been used. 70
35. The combination in a switching system of line circuits, link circuits, trunk circuits, line bars serving said lines, link bars serving said links, a trunk bar for each of said

trunks, means for causing the joint operation of a line bar, a link bar and a trunk bar, said bars cooperating with each other in connecting a line to a link and such link to a trunk, relay means for rendering a selected link inaccessible until all of said links have been used, means for releasing the line and trunk bars, and means controlled by the link bar for maintaining the established connection. 75

6. The combination in a switching system of lines divided into subgroups, a group of links for each subgroup of lines, trunks serving all of said links, line switching members each serving a line in each subgroup, link switching members individual to said links, trunk switching members individual to said trunks, means for causing the joint operation of one of each of said switching members to connect a line to a link and such link to a trunk, and relay means for rendering a selected link inaccessible until all of said links have been used. 80

7. The combination in a switching system of lines divided into subgroups, a group of links for each subgroup of lines, trunks serving all of said links, line switching members, each serving a line in each subgroup, link switching members individual to said links, trunk switching members individual to said trunks, means for causing the joint operation of one of each of said switching members, and relay means for rendering a selected link inaccessible until all of said links have been used. 85

In witness whereof, I hereunto subscribe my name this 7th day of April A. D., 1923. 90

ALFRED F. KANE.
